TRAIN DISPATCHING SYSTEM FOR RAIL-
ROADSOscar H. Dicke and Forest B. Hitchcock, Roches-
ter, N. Y., assignors to General Railway Sig-
nal Company, Rochester, N. Y.

Application March 13, 1929, Serial No. 346,731

23 Claims. (Cl. 246—3)

This invention relates to train dispatching systems, and more particularly to a system in which a plurality of switch machines and wayside signals are controlled and O. S. indications are transmitted by sequentially closed channel or message circuits carried over the same line circuit.

In a selector system of the kind mentioned, suitable apparatus is located at a dispatcher's office and suitable apparatus is located at all way stations, these apparatuses being connected in such a way as to close distinctive channel or message circuits extending from the dispatcher's office to the various way stations sequentially. A system of this kind may for convenience be called a synchronous selector system.

In the prior application of O. H. Dicke, Serial No. 180,475 filed April 2, 1927, a large number of control circuits are momentarily closed sequentially by rotating arms located at the dispatcher's office and at each of the way stations, these rotating arms being rotated in synchronism and being connected by a line wire so that distinctive channel circuits are set up one after another, suitable means being provided to transmit control influences over such momentarily completed channel circuits. In accordance with the present invention it is proposed to use a series of channel selecting relays at the dispatcher's office, and a series of channel selecting relays located at the various way stations along the railway track, these two groups of relays being operated in synchronism so that corresponding relays of each group change simultaneously, so that contacts of these relays may be used to complete channel or message circuits sequentially. Putting it another way, the dispatcher's office, in accordance with the present invention, is provided with a large number of channel selecting relays, say twelve in number, and similarly there are four channel selecting relays at each of the way stations also making a total of twelve. These relays are so interconnected that when the first relay at the dispatcher's office is operated, the first relay at the first way station is operated. Similarly, when the second relay at the dispatcher's office is operated, the second relay at the first way station is operated, and so on, so that when the last or twelfth relay in the dispatcher's office is operated the fourth relay at the third way station is simultaneously operated. By this arrangement the sum of the channel selecting relays located at the way stations is the same as the number of channel selecting relays constituting the relay bank at the dispatcher's office, but if desired there may be more relays in the office group than are used in the way station group as pointed out hereinafter.

Other objects, purposes and characteristic features of the invention are in part apparent

from the accompanying drawings and are in part pointed out in the description hereinafter.

In describing the invention in detail reference will be made to the accompanying drawings in which Fig. 1A illustrates the apparatus located in the dispatcher's office, and Fig. 1B illustrates the apparatus located at the first and second way station of the railway system, these Figs. 1A and 1B preferably being laid end to end to constitute the entire system.

Referring to Fig. 1B wherein there has been shown a passing siding PS of a single track railway system, signaled with absolute-permissive-block signals, of which only the starting signals 2, 2^d, 7 and 7^d, and the entering signals 1, 1^d, 8 and 8^d, have been shown. These signals are controlled jointly by track relays, stick relays and tumble-down circuits, as well as by suitable control relays controlled through the medium of the synchronous relay selector system embodying this invention, and are preferably further controlled in accordance with the position of the associated switch machine SM¹ or SM². Referring to the left hand portion of Fig. 1B the switch machine SM¹ is controlled by the switch machine relay SMR¹ as conventionally shown by dotted line, suitable approach locking and detector locking means being employed as shown in the prior application of S. N. Wight, Serial No. 120,423 filed July 3, 1926. Similarly the switch machine SM² is controlled by the switch machine control relay SMR². The signals 1, 1^d, 8 and 8^d are controlled by the control relays SR¹ and DR², and the signals 1, 1^d, 2 and 2^d are controlled by the control relays SR² and DR¹ as more clearly described in the prior patent to S. N. Wight, Patent No. 1,889,457 dated November 29, 1932. The track switch operated by the switch machine SM¹ is preferably provided with the usual detector track circuit including the detector track relay TR¹, and similarly there is provided a detector track circuit at the east end of the passing siding PS containing a detector track relay TR².

Referring now to Fig. 1A of the drawings, which shows the dispatcher's office, the outlying passing siding PS has been reproduced in miniature by the passing siding ps of a suitable miniature track layout simulating the entire railway system. At the east end of this miniature passing siding ps is shown an indicating lamp l², which in accordance with the present invention, is illuminated when the track relay TR² is de-energized, and similarly there is an indicator l¹ located at the west end of the miniature passing siding ps for indicating the occupancy of the detector track circuit located at the west end of the passing siding PS. This miniature passing siding ps is preferably located over the dispatching machine containing a large number of switch machine and signal levers, of which the signal lever

LS¹ and the switch machine lever LSM¹ are associated with the west end of the passing siding ps, and the levers LS² and LSM² are associated with the east end of the passing siding ps.

5 The dispatcher's office apparatus (entire Fig. 1A) is connected to the first way station (left hand portion of the Fig. 1B) by a message wire 10, a first stepping wire 11, a second stepping wire 12 and a common return wire 13. Similarly, 10 the first way station is connected to a third way station by similar wires.

In the dispatcher's office are located 3 relays, RLR, MR and LR⁰, conveniently called the impulse generating relay group. These relays are 15 so interconnected that the relay RLR controls the relay MR, the relay MR controls the relay LR⁰, and the relay LR⁰ controls the relay RLR to the opposite position from which it occupied when it last controlled the relay MR, so that a 20 sort of non-mechanical or electrical rotation of these relays RLR, MR, and LR⁰ takes place, this rotation discontinuing when the knife switch 19 is opened. If desired the relay RLR may be omitted, which if the other relays have the same operating 25 period speeds up the system. It is thus seen that the line relay LR⁰ the dispatcher's line relay DLR and the line relay LR¹ all three of which are connected in series will be alternately operated from one energized position to the other energized position. The dispatcher's line relay DLR controls the dispatcher's relay group comprising 30 channel selecting relays A, B, C, D, E, F, G. Similarly the line relay LR¹ controls the relay group at the way station containing relays A¹, B¹ and 35 C¹. It will be noted that the line relay LR² is not connected in series with the dispatcher's line relay DLR until the relay C¹ has been operated, but that the line relay LR² when operated may control the relays D², E² and F².

40 From the foregoing description of the relays it readily appears that many different combinations of relay positions may be set up in sequence and that many different channel circuits can be momentarily completed sequentially, so as to constitute 45 a synchronous selector system employing sequentially operated channel selecting relays instead of rotating contact arms. With this general understanding of the system and the specific apparatus involved, it is believed expedient to describe 50 the operation of the system; this in order to understand the particular circuit arrangement selected to illustrate the invention and the manner in which the various relays coact to set up the various channel circuits sequentially.

55 *Operation.*—This apparatus will remain at rest so long as the knife switch 19 is open. All of the polar relays illustrated in the drawings are for conventional purposes so wound that if current flows in at the left hand terminal and out of the 60 right hand terminal of such relay this current flow in co-operation with the magnetism of a permanent magnet associated with such relay will cause its contact to be moved toward the right. In other words, in the convention adopted the application of current of positive polarity 65 to a polar relay moves its contacts toward the right and the application of negative current to the relay causes its contacts to be moved toward the left. Also, in the convention adopted those 70 polar relays in which the movable contacts are shown pendant, that is in a neutral position, are to signify that the particular relay is biased to its neutral position, whereas those relays in which the contact assumes either the right hand or the left hand extreme position and the neutral posi-

tion has not been illustrated signifies that such relay is a polar relay of the magnetic stick type, in which the permanent magnet holds the contacts in the position to which they were last operated.

5 With these conventional representations in mind, closure of the switch 19 causes the contacts 20 and 21 of the master relay MR to be moved to the right, because under this condition the positive terminal of the battery 25 is connected to the left hand terminal of relay MR through the medium of contact 24 of the relay RLR. With the contact 20 in its right hand position positive current is applied to the line relays LR⁰, DLR and LR¹ in series through the following circuit:—beginning at the positive terminal of battery 25, wires 26 and 27, contact 20, wire 28, winding of relay LR⁰, wire 29, winding of the relay DLR, wire 30, contact 31 of the relay G assuming its right hand position, first stepping wire 11, contact 32 of the relay C¹ assuming its right hand position, wire 33, winding of line relay LR¹, wire 34, to common return wire 13, connected to the mid point of the battery 25. It is thus noted that so long as the circuit just traced is not 25 changed by operation of either the group relay G or the group relay C¹, that the line relay LR⁰, DLR and LR¹ will be operated synchronously to the right and left hand positions by repeated 30 reversals of the contact 20 of the master relay MR.

With the line relay LR⁰ in its right hand position current of negative polarity is applied to the repeater line relay RLR through the medium of contact 35 of the line relay LR⁰. This application 35 of negative current to the repeater line RLR causes current of negative polarity to be applied to the master relay MR, thereby causing the master relay to be operated to the left hand extreme position. It is thus seen, that the relays RLR, 40 MR, and LR⁰ will be operated through a cycle of non-mechanical rotation, so that these relays will be alternately operated to their right hand and their left hand extreme position, so long as the switch 19 remains closed.

45 It is thus seen that the line relays LR⁰, DLR, and LR¹ are alternately operated to the right and to the left in synchronism, so long as the circuit connecting these line relays in series is not broken. Let us first observe what effect the dispatcher's 50 line relay DLR will have upon the dispatcher's channel selecting relays A to G, inclusive, and then let us observe what effect the line relay LR¹ will have upon the channel selecting relays A¹, B¹, and C¹.

55 With the dispatcher's line relay DLR operated to the right hand position, current will flow from the positive side of the battery 40, through the contact 39 of relay DLR, contact 41 of the channel selecting relay G assuming the right hand position, then through the contact 42 of the channel selecting relay A assuming the right hand position through the winding of the relay A to a common return wire 13 connected to the mid-point of battery 40. The flow of this current being of positive 60 polarity will have no effect upon the relay A, and the relay A will remain in the right hand position. For reasons already given the line relay DLR will only assume its right hand extreme position momentarily and will then be operated to its left hand position, in which case the negative terminal of the battery 40 is connected to the channel selecting relay A, through the circuit just traced, and this negative application of current to the relay A 65 will cause it to be operated to its left hand position. 70

tion, wherein it is held by permanent magnet stick action. By operation of relay A to the left hand position the shifting of its contact 42 will apply current of negative polarity to the relay B through the medium of contact 43 of the relay B. Since the relay B already assumes the left hand position this application of current of negative polarity thereto will not cause operation thereof. The line relay DLR is, however, after a very short period of time again operated to the right hand extreme position in which case current of positive polarity is applied to the winding of the relay B through the medium of contact 43 of relay B. This application of current of positive polarity to the relay B will cause this relay B to be operated to its right hand position, by reason of which its own energizing circuit is broken and the circuit just mentioned is connected to the relay C through the medium of contact 44 of the relay C. Since this current, however, is of positive polarity and the relay C already assumes the right hand position this application of current will not operate the relay C. The line relay DLR will, however, be operated to the left hand position at the next step of operation, and will apply current from the negative side of the battery 40 to the winding of the relay C through the medium of contacts 39, 41, 42, 43, and 44, and this application of current of negative polarity to the relay C, will cause it to be operated to its left hand position. It is thus seen that operation of the line relay DLR to the right then to the left then to the right and then back to the left has caused operations of the relay A to the left, relay B to the right, and relay C to the left. Let us now see how these same 4 impulses applied to the line relay LR¹ connected in series with the line relay DLR, will produce operations of the channel selecting relays A¹, B¹ and C¹.

As assumed, the first impulse flowing through the line relays in series will operate the line relay LR¹ toward the right, thereby causing the positive side of the battery 45 to be connected to the channel selecting relay A¹ through the medium of contacts 46 of the relay LR¹, 47 of the relay C¹ in its right hand position, and contact 48 of the relay A¹ in its right hand position. This application of positive current to the relay A¹ will not cause operation of this relay A¹, because it already assumes the right hand position. The second current impulse flowing through the line relay LR⁰, DLR and LR¹ in series is of negative polarity, and causes these line relays to be operated to their left hand position, in which case current of negative polarity is applied to the relay A¹ through the medium of contacts 46, 47, and 48, and this application of current of negative polarity causes the relay A¹ to be operated toward the left, whereby the contact 48 of relay A¹ is shifted, and the circuit in question is connected to the relay B¹ through the medium of contact 49 of relay B¹ assuming the left hand position. This application of current of negative polarity to the winding of the relay B¹ will, however, not affect operation of this relay B¹, because it already assumes the left hand position. The next impulse impressed upon the line relay LR¹ is one of positive polarity, thereby moving the contact 46 to the right and applying current of positive polarity to the relay B¹, thereby causing this relay B¹ to be moved to the right, breaking its own energizing circuit and connecting the circuit in question to the winding of the relay C¹, through the medium of contact 50 of the relay C¹. By this application of current of positive polarity to the winding of

relay C¹ the relay C¹ will not be operated, because it already assumes the right hand position.

The next impulse impressed upon the line relay LR¹ is one of negative polarity, thereby moving the contact 46 to the left and applying current of negative polarity to the relay C¹, which causes this relay C¹ to be moved to the left, breaking its own energizing circuit. The operation of the relay C¹ disconnects the line relay LR¹ and passes the impulses to the succeeding station as 10 hereinafter explained.

It is thus seen that channel selecting relays A and A¹ are simultaneously operated toward the left, the channel selecting relays B and B¹ are simultaneously operated toward the right, and 15 the channel selecting relays C and C¹ are simultaneously operated to the left and from which it is understood that the relays A, B, C, and A¹, B¹, and C¹, are operated in non-physical rotation in synchronism, and that contacts of these relays 20 in combination with contacts of adjacent relays may be used to control channel circuits of the synchronous selector system of which they form a part. These channel circuits will be discussed 25 in connection with the transmission of messages both control messages and controlling distant switch machine and signal and indication mechanisms for indicating in the dispatcher's office the occupancy of track circuits along the railway track.

Having now considered how the relays A, B, and C, and the relays A¹, B¹, and C¹ are operated in synchronism, let us consider how the relays D, E, and F, and relays D², and E², and F² are operated in synchronism. The last operated position of the line relays DLR and LR¹ was the left hand position, in which these line relays operated the relay C and C¹ to the left hand position. It should be noted that this operation of the relay C¹ to its left hand dotted position interrupted 40 the line circuit heretofore traced including the relays LR⁰, DLR and LR¹ in series at the contact 32 of the relay C¹, disconnecting the line relay LR¹ and connecting the wire 11 to the wire 15, which wire 15 through contact 54 of relay F² is 45 connected to the winding of the line relay LR², so that the next impulse applied to the line circuit will flow through the line relays LR⁰, DLR and LR² in series, this next line impulse is one of positive polarity and causes the line relays 50 DLR and RL² to be moved toward the right. Current may flow to the relay D from the battery 40, through the medium of contacts 39 of relay DLR toward the right, contact 41 of relay G, in its right hand position, contact 42 of relay A in 55 its left hand position, contact 43 of relay B in its right hand position, contact 44 of relay C in its left hand position, and contact 56 of relay D in its left hand position, thus operating the relay D to its right hand position. Similarly operation 60 of the line relay LR² to its right hand position, causes current to flow from the positive side of battery 55, through the contact 53 of relay LR², contact 60 of relay F² assuming its left hand position, through contact 51 of the relay D² assuming its left hand position to the winding of this relay D². This application of current of positive polarity to the relay D² causes it to be operated to its right hand position, as a result of which the circuit in question is shifted to the relay E² through the medium of contact 52, but since this relay E² already assumes the right hand position it will not respond to this flow of current of positive polarity.

The next impulse applied to the line relays 75

LR⁰, DLR and LR² in series, is of negative polarity, thereby causing these line relays to be operated toward the left. With the line relay DLR now assuming the left hand position, current of negative polarity is applied to the relay E, from the battery 40 through the contact 39 of relay DLR, contact 41 of relay G, to the right, contact 42 of relay A to the left, contact 43 of relay B to the right, contact 44 of relay C to the left, contact 56 of relay D to the right and contact 57 of relay E in its right hand position to the winding of relay E thereby operating the relay E to the left hand position, and continuing the circuit in question through the contact 58 of the relay F to the winding of the relay F. This relay F, however, already assumes the left hand position so that it will not be operated until the line relay DLR is moved back to its right hand position. Similarly, operation of the line relay 20 LR² to its left hand position causes current of negative polarity to be applied to the relay E² from the battery 55, through contact 53 of relay LR² to the left, contact 60 of relay F² to the left, contact 51 of relay D² assuming the right hand 25 position, contact 52 of the relay E², assuming its right hand position, whereby the relay E² is operated toward the left and shifts the circuit in question to the winding of the relay F² through contact 61 of this relay, but since the current is 30 of negative polarity the relay F² is not operated.

The line relays DLR and LR² are now operated toward the right, under which condition current of positive polarity from the battery 40 may flow to the winding of the relay F through 35 the contact 39 of the relay DLR to the right, contact 41 of the relay G assuming its right hand position, contact 42 of the relay A to the left, contact 43 of the relay B to the right, contact 44 of the relay C to the left, contact 56 of the relay 40 D to the right, contact 57 of the relay E to the left, contact 58 of the relay F assuming its left hand position, through the winding of relay F to the common connection of the battery, whereby relay F is operated to its right hand position. 45 Similarly, operation of the line relay LR² to its right hand position applies current of positive polarity from battery 55 through contact 53 of relay LR², contact 60 of relay F² assuming its left hand position, contact 51 of relay D² assuming 50 its right hand position, contact 52 of relay E² assuming its left hand position, contact 61 of relay F² assuming its left hand position, to the winding of this relay F², thus operating the relay F² to its right hand position. This operation of 55 the relay F² to its right hand position disconnects the line relay LR² and connects the line relay of the next way station (not specifically shown). Impulses applied to the first stepping circuit will 60 not operate any of the relays at either the first or the second way station hereafter, but if impulses are applied to the second stepping circuit the relays are again operated sequentially as hereinafter explained from which it appears that if the relays at the way stations should lose or 65 gain one or more steps they will be automatically brought back in step upon shifting of the control from the first stepping line to the second stepping line, as presently described.

In the operation as thus far considered, the 70 repeated reversals of the master relay MR caused the relays A, B, C, D, E, and F and the relays A¹, B¹, C¹, D², E², and F² to be successively operated from their solid line to their dotted line position, the relays A and A¹ being operated first 75 and the relays F and F² being operated last

during each half cycle. The next impulse that is applied to the line circuit is a negative impulse and operates the relay DLR to the left hand position, and causes the relay G to be operated to the left hand position through the following circuit:—beginning at the negative terminal of the battery 40, contact 39 of the relay DLR in its left hand position, contact 41 of the relay G in its right hand position, contact 42 of relay A toward the left, contact 43 of the relay B toward the right, contact 44 of the relay C toward the left, contact 56 of the relay D toward the right, contact 57 of the relay E toward the left, contact 58 of the relay F toward the right through the contact 59 of the relay G and the winding of this 15 relay to the mid-point of battery 40. This impulse causing the relay G to be operated to its left hand dotted position. The shifting of the relay G to its dotted position causes the contact 31 to connect the line wire 30 from the first stepping wire 11 to the second stepping wire 12, and with negative current still applied to the line wire 30 it may flow through the contact 31 in its left hand position, through wire 12 through the contact 70 in its left hand position, through wire 25 33 to the winding of relay LR¹, wire 34 and common return wire 13, back to the battery 25. But this application of current of negative polarity to the line relay LR¹ will not cause operation of the relay A¹ through the contact 46 of relay LR¹ 30 in its left hand position, and contact 47 of relay C¹ in its left hand position, and contact 71 of the relay A¹ in its left hand position to the winding of relay A¹, because this relay A¹ already assumes the position to which current of negative 35 polarity would operate it. In other words, the relay G in the dispatcher's office has been operated to shift the stepping impulses to the second stepping wire, but this stepping impulse has not caused operation of any of the relays A¹, B¹, 40 C¹, D², E², and F² at the way stations.

The master relay MR is next operated to the right, in which position current from the positive side of battery 25 may flow through the line relays LR⁰, DLR, and LR¹ for reasons just given, 45 namely because relay G now assumes the left hand dotted position. With the line relay DLR operated to its right hand position current of positive polarity is applied to the relay A through the following circuit:—beginning at the positive 50 terminal of battery 40, contact 39 of the relay DLR to the right, contact 41 of the relay G, toward the left, contact 63 of the relay A to the left, thus operating the relay A to its right hand position, and thus breaking the circuit just traced 55 and shifting it to the winding of the relay B, which will not be operated. Similarly, operation of the line relay LR¹ to its right hand position, causes current to flow from the positive side of the battery 45, through contact 46 of the line 60 relay LR¹ to the right, contact 47 of relay C¹ to the left, contact 71 of relay A¹ to the left, through the winding of this relay A¹, back to the mid-point of battery 45, thus causing the relay A¹ to be operated toward the right, in which case 65 the circuit just traced is shifted to the relay B¹, which relay B¹ is not operated for obvious reasons.

The line relays DLR and LR¹ are next operated toward the left. This causes the relay B to be 70 operated toward the left through the following circuit:—beginning at the negative terminal of battery 40, contact 39 of relay DLR to the left, contact 41 of relay G to the left, contact 63 of relay A to the right, and contact 64 of the relay B to the right, and causes the relay B to be 75

operated toward the left. Similarly the channel selecting relay B¹ is operated in response to operation of relay LR¹ to the left through the following circuit:—beginning at the negative terminal of the battery 45, contact 46 of the line relay LR¹ to the left, contact 47 of the relay C¹ to the left, contact 71 of the relay A¹ to the right, and contact 72 of the relay B¹ to the right, thus causing the relay B¹ to be operated toward the left.

The relays DLR and LR¹ are next operated toward the right, in which case relay C is operated toward the right through the following circuit:—beginning at the positive terminal of battery 40, contact 39 of relay DLR to the right, contact 41 of relay G toward the left, contact 63 of relay A toward the right, contact 64 of relay B toward the left, contact 65 of relay C toward the left, thus causing the relay C to be operated toward the right. The relay C¹ is operated toward the right through the following circuit:—beginning at the positive side of battery 45, contact 46 of relay LR¹ to the right, contact 47 of the relay C¹ to the left, contact 71 of the relay A¹ to the right, contact 72 of the relay B¹ to the left and through contact 50 of the relay C¹ to the left, through winding of the relay C¹, thus causing the relay C¹ to be operated toward the right, and thereby shifting the contact 70 from its dotted to the solid line position and substituting the line relay LR² for the line relay LR¹ in the second stepping circuit.

The line relays DLR and LR² are next operated toward their left hand position, in response to which the relay D is operated to the left through the following circuit:—beginning at the negative terminal of battery 40, contact 39 of relay DLR to the left, contact 41 of relay D to the left, contact 63 of relay A to the right, contact 64 of relay B to the left, contact 65 of relay C to the right, contact 66 of relay D to the right, through the winding of the relay D, thus operating the relay D¹ to its left hand position. The relay D² is similarly operated to the left through the following circuit:—beginning at the negative terminal of the battery 55, contact 53 of the relay LR² to the left, contact 60 of the relay F² to the right, contact 75 of the relay D² to the right, through the winding of this relay D², thus operating this relay D² back to its left hand normal position.

The line relays DLR and LR² are next operated to their right hand position in which case the relay E is operated to its right hand position through the following circuit:—beginning at the positive terminal of the battery 40, contact 39 of the relay DLR to the right, contact 41 of the relay G to the left, contact 63 of the relay A to the right, contact 64 of the relay B to the left, contact 65 of the relay C to the right, contact 66 of the relay D to the left, contact 67 of the relay E to the left, thus causing the relay E to be operated toward the right. Similarly the relay E² is moved to its right hand position through closure of the following circuit:—beginning at the positive terminal of battery 55, contact 53 of the line relay LR² to the right, contact 60 of the relay F² to the right, contact 75 of the relay D² to the left, through the winding of this relay E² to the left, thus causing operation of the relay E² toward the right.

The line relays DLR and LR² are next operated to their left hand positions in which case the relay F is operated to its left hand position

through the following circuit:—beginning at the negative terminal of battery 40, contact 39 of relay DLR to the left, contact 41 of relay G to the left, contact 63 of relay A to the right, contact 64 of relay B to the left, contact 65 of relay C to the right, contact 66 of relay D to the left, contact 67 of the relay E to the right, contact 68 of the relay F to the right, thus causing the relay F to be operated to its left hand position. Similarly the relay F² is operated to its left hand position through the following circuit:—beginning at the negative terminal of the battery 55, contact 53 of the relay LR² to the left, contact 60 of the relay F² to the right, contact 75 of the relay D² to the left, contacts 76 of the relay E² to the right, contact 61 of the relay F² to the right, thus causing the relay F² to be operated toward its left hand position.

This operation of the relay F² to its left hand position disconnects the line relay LR² from the second stepping wire through the medium of the contact 79, so that impulses over the second stepping wires 12 and 16 will not operate the line relay LR². The line relay DLR is next operated to its right hand position, thereby operating the relay G to the right hand position through a circuit readily traced, bearing in mind that the relays A to F, inclusive, assume their normal position.

It is thus seen that the non-physical rotation of the relays MR, LR⁰, and RLR causes the channel selecting relays of like reference character (disregarding the exponents) to be operated successively from their normal to their dotted position, and after all of these relays have been operated to their dotted position causes them to be operated back to their normal position sequentially and in synchronism. These channel selecting relays are all at rest long enough between successive operations thereof to complete distinctive message or channel circuits, bearing in mind that although a particular channel selecting relay is shifted it remains in the shifted position for some time but that its relation of position to the next adjacent relay is only maintained until the next succeeding relay is operated. In other words, if a circuit is taken through the right hand contacts of two adjacent relays this circuit is only maintained from the time that the first of these relays is operated until the second of these relays is operated.

Let us now assume that the lever LS¹ has been moved toward the left, and let us trace the channel circuit over which the relay DR¹ is controlled by the lever LS¹, the message channel for which is closed only while the relays A and B and the relays A¹ and B¹ assume their left hand positions, which can only happen when all of the channel selecting relays of the two groups except the relays A and A¹ assume their normal position, which relays presumably have just been operated to their dotted position. This circuit may be traced as follows:—beginning at the negative terminal of the battery 25, wires 80 and 81, contact LS¹ toward the left, wire 82, contact 83 toward the left, wire 84, contact 85 toward the left, wire 86, contact 87 toward the right, wire 88, contact 89 toward the left, wire 90, contact 91 toward the right, wire 92, contact 93 toward the left, wire 94, contact 23 toward the right, wire 95, contact 21 toward the left, message wire 10, wire 96 (see Fig. 1B), contact 74 to the right, wire 97, contact 98 toward the left, wire 99, contact 100 toward the left, wire 75

101, winding of the direction relay DR¹, through wires 102, 103 and 104, back through the common return wire 13 connected to the midpoint of battery 25, so that operation of the lever LS¹ toward the left causes the direction relay DR¹ to be operated toward the left.

Similarly, since the lever contact 105 is mechanically connected to the lever LS¹ the contact 105 is also operated toward the left, thereby applying current of positive polarity to the signal relay SR¹ through the following circuit:—starting at the positive side of battery 25, in the dispatcher's office, wires 26, 106, 107, and 108, contact 105, wire 109, contact 110 of the relay B 15 in its left hand position, wire 111, contact 112 of the relay C in its left hand position, wire 113, contact 114 of the relay D in its right hand position, wire 115, contact 116 of the relay E in its left hand position, wire 117, contact 93 of the 20 relay F in its right hand position through the wire 94, contact 23 of the relay LR⁰ in the right hand position, wire 95, contact 21 of the relay MR in its left hand position, message wire 10, wire 96 (see Fig. 1B), contact 74 in its left hand 25 dotted position, wire 111, contact 73 in its left hand position, wire 112 through the winding of signal relay SR¹, through the wires 113, 114, 103 and 104, to common return wire 13 connected to the midpoint of battery 25.

30 Let us now assume that the dispatcher wishes to operate the switch machine SM¹ to the take-siding position in response to operation of the switch machine relay SMR² to its left hand position, and to accomplish this he operates the lever LSM¹ toward the left. The circuit through which the lever LSM¹ may operate the relay SMR, which is closed only when the relays B and C as well as the relays B¹ and C¹ all assume their right hand position, and may be traced as 35 follows:—beginning at the negative terminal of the battery 25, wire 80, 81, and 120, lever contacts LSM¹ to the left, wire 121, contact 85 of the relay B in its right hand position, wire 86, contact 87 of the relay C in its right hand position, wire 45 88, contact 89 of the relay D in its left hand position, wire 90, contact 91 of the relay E in its right hand position, wire 92, contact 93 of the relay F in its left hand position, wire 94, contacts 23 of the relay LR⁰ in its left hand position, wire 22, 50 contact 21 of the relay MR toward the right, message wire 10, wire 96 (see Fig. 1A), contact 74 of the relay C¹ toward the right, wire 97, contact 98 of the relay B¹ toward the right, wire 123, winding of the relay SMR¹, wires 124, 114, 103, 55 104, common return wire 13, back to the midpoint of battery 25. The completion of this circuit operates the switch machine relay SMR¹ toward the left, thereby operating the switch machine SM¹ toward the take-siding position, in 60 a manner as more clearly described in the Wight application, Ser. No. 120,423 above referred to.

Similarly, the circuit for operating the direction relay DR² toward the left completed when the lever LS² is moved toward the left during 65 the period the relays E, F, E² and F² assume the left hand position, may be traced as follows:—beginning at the negative terminal of battery 25, wires 88, 81, 120, and 125, contact LS² in its left hand position, wire 126, contact 91 of relay 70 E toward the left, wire 92, contact 93 of relay F toward the left, wire 94, contact 23 of the relay LR⁰ toward the left, wire 22, contact 21 of the relay MR toward the right, message wire 10, wire 128 (see Fig. 1B), contact 77 of relay F² toward 75 the left, wire 129, contact 130 of relay E² toward

the left, wire 131, winding of the direction relay DR², wires 132, 133, 134, and 135, to common return wire 13, back to the midpoint of battery 25.

Similarly, the signal relay SR² is operated to its right hand position during the short period 5 while the relays D, E, and D² and E² assume their right hand position, in response to this operation of the lever LS² toward the left through the following circuit:—beginning at the positive terminal of battery 25, wires 26, 106, and 108, contact 141 of the lever LS², wire 142, contact 39 of the relay D in its right hand position, wire 90, contact 91 of the relay E in its right hand position, wire 92, contact 93 of the relay F in its left hand position, wire 94, contact 23 in its right hand position, wire 95, contact 21 of relay MR in its left hand position, message wire 10, wire 128 at the second way station, (see Fig. 1A) contact 77 of the relay F² in its left hand position, wire 129, contact 130 of the relay E² in its right hand position, wire 145, contact 146 of the relay D² in its right hand position, wire 147, winding of the signal relay SR², wires 148, 134, 135 and common return wire 13, back to the midpoint of battery 25.

Similarly, the switch machine relay SMR² may be operated toward its left hand dotted position by movement of the lever LSM² to its left hand position, through the following circuit, closed when the relays D and E, and the relays D² and E² assume their left hand position:—beginning at the negative terminal of battery 25, wires 80, 81, 120, 125 and 150, lever LSM² in its left hand position, wire 151, contact 114 of the relay D in its left hand position, wire 115, contact 116 of relay E in its left hand position, wire 117, contact 93 of relay F in its right hand dotted position, wire 94, contact 23 of the relay LR⁰ in its left hand position, wire 22, contact 21 of relay MR in its right hand position, message wire 10, wire 128 (see Fig. 1B), contact 77 of relay F in its right hand position, wire 132, contact 153 of the relay E² in its left hand position, wire 154, contact 155 of the relay D² in its left hand position, wire 156, winding of the switch machine relay SMR², through wires 157, 133, 134, 135, and common return wire 13, back to the midpoint of battery 25.

Let us now consider the operation in connection with transmitting the condition of occupancy of the detector track circuit containing track relay TR¹ to the dispatcher's office, by illumination of the indicating lamp I¹. Let us assume that the relay TR¹ has been dropped by passing train, thereby reversing the polarity of current from the following circuit:—beginning at the negative side of the battery 160, contact 161 of the relay TR¹ in its retracted position, wire 162, contact 163 of the relay A¹ in its right hand position, wire 164, contact 73 of the relay B¹, in its right hand position, wire 111, contact 74 of the relay C¹ in its left hand position, wire 96, message wire 10, contact 21 of the master relay MR in its left hand position, wire 95, contact 23 of the relay LR⁰ in its right hand position, wire 94, contact 93 of the relay F in its right hand position, wire 117, contact 116 of the relay E in its left hand position, wire 115, contact 114 of the relay D in its right hand position, wire 113, contact 112 of the relay C in its left hand position, wire 111, contact 110 of the relay B in its right hand position, wire 165, contact 166 of the relay A in its right hand position, wire 167, winding of indication relay IR¹ through common return wire 13, wires 104 and 108, back to the

midpoint of battery 160. The completion of this circuit, even though only momentarily, operates the indication relay IR¹ toward the left thereby illuminating the indicating lamp I¹ until the track relay TR¹ again picks up and re-applies current of positive polarity to the indicating relay IR¹.

Let us now see how de-energization of the track relay TR² applies current of negative instead of positive polarity to the indication relay IR² through the momentarily completed message channel completed only when the relays E, F, and E² and F² all assume their right hand position. This circuit may be traced as follows:—

15 starting at the negative terminal of battery 170, contact 171 of the track relay TR² assuming its retracted position, wire 172, contact 153 of the relay E² in its right hand position, wire 152, contact 17 of the relay F² in its right hand position, wire 128, message wire 10, contact 21 of the master relay MR assuming its left hand position, wire 95, contact 23 of the relay LR⁰ assuming its right hand position, wire 94, contact 93 of the relay F assuming its right hand position, wire 25 117, contact 116 of the relay E assuming its right hand position, wire 174, winding of the indicating relay IR², to common return wire 13, wire 135 (second way station), wire 175 connected to the midpoint of battery 170. The completion of 30 this circuit with the contact 171 of track relay TR² in its retracted position causes current of negative polarity to be applied to the indication relay IR², thereby causing its polar contact to be moved to the left to complete the energizing 35 circuit for the indicating lamp I².

In view of the foregoing it is noted that in each case where a channel selecting relay is operated, whether in the dispatcher's office or at a way station, it must break its own energizing 40 circuit before it has completed its movement. This is not a difficult matter because the type of relay used includes a permanent magnet which tends to operate the relay contacts to their extreme position as soon as they have moved beyond their middle position. If desired the contact carrying the energizing circuit of its own relay winding may be constructed to be made until the relay has moved beyond center, that is, to be a break-beyond-center contact, so that 45 50 the momentum of the armature of the relay need not be relied upon to carry it over center. The master relay MR and the line relay DLR, LR¹ and LR² are preferably biased to their neutral position as conventionally shown.

55 Attention is directed to the fact that each channel circuit is carried through the contact 23 of relay LR⁰ and contact 21 of relay MR. This is done in order to cut down the channel time considerably below the maximum channel 60 time. In this connection it should be noted that the contacts 21 and 23 must be out of correspondence to complete a channel circuit, or in other words, the channels may be closed only during the time line relay LR⁰ is energized but has not 65 yet responded to such energization. This line relay LR⁰ may be slow-acting as compared with relays RLR and MR, so that the proper channel time may be obtained.

Applicants have thus described how the various 70 channel selecting relays of the bank or group may be operated in synchronism and sequentially one after the other in alphabetical order, and have pointed out the operation of these relays, and how these relays are again brought into synchronism if they should for some reason

or other get out of synchronism, this being carried out by transferring from the first stepping line to the second line, so that the relay A is at each time operated when the relay A¹ is operated for each half cycle of relay operation. Applicants 5 have then pointed out how the distinctive message channels are closed one at a time, each of which channel circuits remains closed only so long as two adjacent relays in the bank series assume like positions, it being noted that when all of the relays 10 assume their normal position adjacent relays assume unlike polar positions and also that when all of relays assume their abnormal dotted position adjacent relays of the bank assume unlike positions, from which it appears that if the channel 15 circuit is taken through like polarity contacts of two adjacent relays such channel is completed only during one step of the entire cycle of relay operation. It is to be understood that the arrangement shown may be extended to any number 20 of stations instead of only two stations, as illustrated, and that any number of relays may be used at a particular way station instead of the three relays A¹, B¹ and C¹ or the relays D² and E² and F², as shown. Attention is particularly 25 directed to the economy in relays required in the system described, in that there is only one way station channel selecting relay for each dispatcher's channel selecting relay, that is, the entire relay series is not repeated at each way station, only those relays required at a particular way station are located at such way station. Putting it another way, the non-physical rotation accomplished by relays lends itself admirably to 30 distribution of a single cycle synchronous mechanism along the entire railroad so that a single relay group may be parcelled along the entire railroad and duplication of devices is eliminated. Looking at the arrangement shown and described in a little different way, the railroad system is 40 divided into way stations or sections with relays located at each way station in which the relays are so interconnected that first one way station is selected, the bank of relays at that way station are successively stepped to the reverse position 45 from what they then assumed, after which the next way station may be stepped along one after another, and so on, until all of the way stations have had the relays of their banks shifted to the reverse position from what they previously 50 assumed.

The present invention of which only one specific embodiment has been illustrated is, of course, understood to be of broader application than the specific arrangement shown. For instance, it 55 appears, that in accordance with the present invention, that a synchronously operated selector mechanism may be located at each of a plurality of way stations and that these synchronous selector mechanisms may be operated one at a time, 60 by the respective line relay of the way station then being operated. Although banks of relays have been illustrated as one form of a synchronous selector mechanism usable at a way station, it should be understood that some other 65 form of synchronous selector mechanism, such as the mechanism shown in the application of Neil D. Preston, Ser. No. 199,325 filed June 16, 1927, may be used instead of the banks of channel selecting relays shown. Also, although the particular system illustrating the present invention is one which is intended to be operated continuously except when the hand switch 19 is open, it should be understood that the system may be 70 readily modified as disclosed in the joint appli- 75

cation of Hitchcock and Dicke, Ser. No. 345,667, filed March 9, 1929, in which the system is normally at rest but is automatically initiated into action either when a change in traffic conditions 5 takes place which should be indicated in the dispatcher's office through suitable OS signalling means, or is initiated into action when a lever has been operated in the dispatcher's office to enable the control of said lever to be transmitted 10 to the particular distant way station.

Having thus shown and described one particular system for carrying out the present invention, it is desired to be understood that the particular system shown has been selected for the 15 purpose of disclosing the underlying principles of the invention rather than its scope or the particular circuit arrangement preferably employed in practicing the same, and that certain features of the system may be omitted; for instance, the message circuit need not be carried 20 through the contact 23 of the relay LR⁰ and the contact 21 of the relay MR, unless desired, or the line relays LR¹, LR², etc. may be omitted in which event the stepping circuit would be connected 25 directly to the contacts of relays A¹ or D², as the case may be, instead of to the corresponding line relays LR¹ or LR², and that various changes, modifications, and additions may be made to the particular arrangement shown to 30 apply the system to fit the particular problem encountered in practicing the invention all without departing from the spirit or scope of the invention or the idea of means underlying the same, except as demanded by the scope of the following 35 claims.

What we claim is:—

1. In a train dispatching system, the combination with a dispatcher's office and a plurality of way stations; of switch machines and signals at 40 the way stations and indicators at said dispatcher's office; and a synchronous selector system for controlling said switch machines, signals, and indicators comprising; a dispatcher's channel selecting relay bank located at the dispatcher's 45 office, a line relay at the dispatcher's office for controlling the selecting operation of said dispatcher's channel selecting relay bank, a way station channel selecting relay bank having relays corresponding in number respectively to the relays of said dispatcher's channel selecting 50 relay bank and having its relays distributed among the various way stations, a line relay for each of said way stations for controlling the selecting operation of said channel selecting 55 relays at its respective way station, means for operating the channel selecting relays of the dispatcher's channel selecting relay bank successively in a certain order, means for placing said line relays at the several way stations successively 60 and sequentially in multiple in a line circuit with said line relay at said dispatcher's office, whereby the way station channel selecting relays are operated sequentially and in synchronism with their corresponding channel selecting relays at the dispatcher's office, and whereby the way station 65 channel selecting relays are operated at only one station at a time, and a plurality of message circuits each including the same message and return line wires completed successively during a 70 cycle of said channel selecting relays, each of said message circuits including contacts of two adjacent relays of the dispatcher's channel selecting relay bank, and each of said message channel circuits being used to control a particular signal, 75 indicator or switch machine.

2. A train dispatching system of the synchronous selector type for controlling traffic controlling devices of railroads comprising, a dispatcher's office, a plurality of way stations, a separate line relay for said dispatcher's office and for each of said way stations, a dispatcher's channel selecting relay bank comprising a plurality of relays operated successively by and in accordance with repeated operations of said dispatcher's line relay, a way station channel selecting relay bank each relay of which corresponds to a particular relay of the dispatcher's relay bank these relays being distributed along the railway track in a manner to associate two or more relays with each of said way station line relays 10 operating the same, means for successively connecting said way station line relays one at a time in series with said dispatcher's line relay said line relays and channel selecting relays being so interconnected that upon sequential operation of the relays of the dispatcher's bank by the dispatcher's line relay the corresponding relays of the way station bank are operated in synchronism therewith through the medium of their associated line relay, a plurality of message circuits completed successively and each including the same line wire and common return wire and contacts of corresponding relays of the dispatcher's bank and of the way station bank. 15 20 25

3. A train dispatching system of the synchronous selector type for controlling traffic controlling devices of railroads comprising, a dispatcher's office, a plurality of way stations, a separate line relay for said dispatcher's office and for each of said way stations, a dispatcher's 30 bank of channel selecting relays operated successively by repeated operations of said dispatcher's line relay, a small bank of channel selecting relays for each way station operated successively by repeated operations of the line relay of the 35 corresponding way station, the channel selecting relays of all the small banks together constituting the way station relay bank and each relay thereof corresponding to a particular relay of the dispatcher's office bank, means for connecting 40 said dispatcher's line relay in series with said way station line relays successively one at a time in a manner to cause the channel selecting relays of the dispatcher's relay bank to be operated synchronously with corresponding channel selecting 45 relays of the way station relay bank, and a plurality of message circuits each including the same line and return wire and including the contacts of corresponding channel selecting relays of the dispatcher's relay bank and of the way 50 station relay bank. 55

4. A train dispatching system of the synchronous selector type for controlling traffic controlling devices of railroads comprising, a dispatcher's office, a plurality of way stations, a separate 60 line relay for said dispatcher's office and for each of said way stations, a dispatcher's bank of channel selecting relays operated successively by repeated operations of said dispatcher's line relay, a way station bank of channel selecting relays 65 divided into groups to provide a group for each way station line relay, the relays of each group being controlled to be operated successively by repeated operations of such line relay, means for connecting said dispatcher's line relay in series 70 with said way station line relays successively one at a time for periods to cause the channel selecting relays of the dispatcher's relay bank to be operated synchronously with corresponding channel selecting relays of the way station relay 75

bank, and a plurality of message circuits each including the same message wire and common return wire and contacts of two corresponding and synchronously operated channel selecting relays one of the dispatcher's bank and the other of the way station bank.

5. A train dispatching system of the synchronous selector type for controlling traffic controlling devices of railroads comprising a dispatcher's office, a plurality of way stations, a stepping circuit connecting said dispatcher's office and said way stations, a dispatcher's bank of channel selecting relays of which individual relays are operated successively by repeated energizations of said stepping circuit, the operation of each relay completing a circuit for operating the next succeeding relay by the next impulse, a way station bank of channel selecting relays divided into groups to provide one group for each way station, each way station channel selecting relay corresponding to one relay of the dispatcher's relay bank and the relays of the way station bank being operated successively in response to repeated energizations of said stepping circuit, the 10 operation of each relay completing a circuit for operating the next succeeding relay by the next impulse, so that corresponding relays of the dispatcher's bank and the way station bank are operated simultaneously and always assume corresponding positions, said dispatcher's relay bank and way station relay bank including means for resynchronizing the relays in the event the relays of one or the other of these banks gain or lose one or more steps, and a plurality of message circuits closed sequentially each including the same line wire and common return wire and each including contacts of two corresponding and synchronously operated channel selecting relays respectively of the dispatcher's bank and the 15 way station bank.

6. A train dispatching system of the synchronous selector type for controlling traffic controlling devices of railroads comprising, a dispatcher's office, a plurality of way stations, a separate line relay of the polar type for said dispatcher's office and for each of said way stations, a dispatcher's office channel selecting relay bank comprising a plurality of relays operated successively by and in accordance with the 20 polar position of said dispatcher's line relay, a way station channel selecting relay bank each relay of which corresponds to a particular relay of the dispatcher's relay bank these relays being distributed along the railway track in a manner to associate two or more relays with each of said way stations and, means for successively connecting said way station line relays one at a time in series with said dispatcher's line relay, said polar line relays and channel selecting relays being so interconnected that upon 25 sequential operation of the relays of the dispatcher's bank by the dispatcher's line relay the corresponding relays of the way station bank are operated in synchronism therewith through the medium of their associated line relay, a plurality of message circuits completed successively and each including the same line wire and common return wire and contacts of corresponding relays of the dispatcher's bank and of the way station bank.

7. A train dispatching system of the synchronous selector type for controlling traffic controlling devices of railroads comprising, a dispatcher's office, a plurality of way stations, a 30 separate polar line relay for said dispatcher's of-

5. A train dispatching system of the synchronous selector type for controlling traffic controlling devices of railroads comprising a dispatcher's office, a plurality of way stations, a stepping circuit connecting said dispatcher's office and said way stations, a dispatcher's bank of channel selecting relays for each way station operated successively by repeated reversals of the line relay of the corresponding way station, the channel selecting relays of all the small banks together constituting the way station relay bank and each relay thereof corresponding to a particular relay of the dispatcher's office bank, means for connecting said dispatcher's line relay in series with said way station line relays successively one at a time in a manner to cause the channel selecting relays of the dispatcher's relay bank 10 to be operated synchronously with corresponding channel selecting relays of the way station relay bank, and a plurality of message circuits each including the same line and return wire and including the contacts of corresponding channel 15 selecting relays of the dispatcher's relay bank and of the way station relay bank.

8. A train dispatching system of the synchronous selector type for controlling traffic controlling devices of railroads comprising, a dispatcher's office, a plurality of way stations, a separate line relay of the polar type for said dispatcher's office and for each of said way stations, a dispatcher's bank of channel selecting relays operated successively by repeated reversals 20 of said dispatcher's line relay, a way station bank of channel selecting relays divided into groups to provide a group for each way station line relay, the relays of each group being controlled to be operated successively by repeated reversals 25 of such line relay, means for connecting said dispatcher's line relay in series with said way station line relays successively one at a time for periods to cause the channel selecting relays of the dispatcher's relay bank to be operated synchronously with corresponding channel selecting relays of the way station relay bank, and a plurality of message circuits each including the 30 same message wire and common return wire and contacts of two corresponding and synchronously operated channel selecting relays one of the dispatcher's bank and the other of the way station bank.

9. A train dispatching system for controlling the movement of trains in response to dispatcher controlled wayside signals comprising, a dispatcher's office, a plurality of way stations, two stepping wires, a message wire and a common wire connecting said dispatcher's office with each of said stations successively, a dispatcher's bank of polar channel selecting relays, a way station bank of polar relays divided into groups one group for each way station and one relay for each relay in the dispatcher's bank, means including said two stepping wires for simultaneously operating the polar relays of the dispatcher's bank and the corresponding polar relays of the way station bank to correspond polar positions, and a plurality of sequentially closed channel circuits each including said message wire and said common wire and including corresponding polar contacts of corresponding polar relays of the two relay banks.

10. A train dispatching system for controlling the movement of trains in response to dispatcher controlled wayside signals comprising, a dispatcher's office, a plurality of way stations, a dispatcher's bank of polar channel selecting relays, a way station bank of polar relays divided into groups one group for each way station and one 70

75

relay for each relay in the dispatcher bank, means for simultaneously operating the polar relays of the dispatcher's bank and the corresponding polar relays of the way station bank to corresponding polar positions, and a plurality of sequentially closed channel circuits each including the same line wire, common return wire and corresponding polar contacts of corresponding polar relays of the two relay banks and also including contacts for restricting the time during which these channels may be completed.

11. A train dispatching system for controlling the movements of trains by controlling wayside signals at a plurality of way stations from a central dispatcher's office, a stepping wire connecting the dispatcher's office with the plurality of way stations, a line relay at the dispatcher's office and at each of the way stations controlled by current flowing over said stepping wire, a group of channel selecting relays at the control office and at each of said way stations so associated with their respective line relays as to be operated sequentially in response to repeated operations of the associated line relay, means including said groups of channel selecting relays at the way stations for rendering said line relays successively responsive one at a time to current in said stepping wire to control their respective channel selecting relays, and means for controlling said wayside signals including contacts of said channel selecting relays at the dispatcher's office and contacts of the channel selecting relays at the particular way station where such wayside signals are located.

12. A train dispatching system for controlling the movement of trains in response to wayside signals comprising; a dispatcher's office; a plurality of way stations; a stepping wire; a line relay at each way station controlled by current flow in said stepping wire; a synchronous selector mechanism associated with each of said line relays, each of said mechanisms being responsive to operate step-by-step in response to repeated operations of its associated line relay; means including the synchronous selector mechanisms at the way stations for rendering said line relays successively responsive one at a time to current in said stepping wire to thereby control their respective mechanisms; and means for controlling said wayside signals including contacts controlled by said synchronous selector mechanisms.

13. In a centralized traffic controlling system, the combination with a central office and a plurality of way stations, of a series of channel selecting relays at each way station, a channel selecting relay in the central office for each way station channel selecting relay, a line relay in said central office and at each way station, means including said line relays to cause said central office channel selecting relays and their corresponding way station selecting relays to operate sequentially and also including a line wire connecting adjacent way stations for causing the first channel selecting relay of a particular way station to operate the next step after the last channel selecting relay of the next preceding way station has been operated, and a plurality of message circuits each including channel selecting relay contacts and the same line wire rendered available sequentially to control traffic controlling devices at said way stations.

14. In a centralized traffic controlling system for railroads; the combination with a central office and a plurality of way stations, of a line

relay at each way station, a first line wire section connecting said central office to the first way station, a second line wire section connecting said first way station to the second way station, a message wire connecting said central office and all of said way stations, means at said central office and at said way stations for closing a large number of message circuits each including said message wire sequentially and controlled by apparatus at said central office and the line relays at said way stations, station selecting means at each way station for disconnecting the line relay at said way station and connecting the line wire section toward the rear to the line wire section in advance, and other sections of line wires connecting the first way station to the central office and each way station to the next more distant way station for returning said station selecting means back to its normal position.

15. In a centralized traffic controlling system for railroads; the combination with a central office and a plurality of way stations, of a line relay at each way station, a message circuit connecting said central office and all of said way stations, one line circuit divided into sections each section connecting two adjacent way stations, another line circuit also divided into sections each connecting two adjacent way stations, a line relay at each way station, two position means at each way station for either connecting the line relay at such way station to said one line circuit and connecting the adjacent sections of said another line circuit together or connecting the line relay at such way station to said another line and connecting the adjacent sections of said one line circuit together, whereby the line relay at each way station may be individually connected to either said one or said another line circuit and a railway signal at each way station controlled over said message wire through the medium of said line relays.

16. In a centralized traffic controlling system for railroads; the combination with a central office and a plurality of way stations, of a line relay at each way station, a message circuit connecting said central office and all of said way stations, one line circuit divided into sections each section connecting two adjacent way stations, another line circuit also divided into sections each connecting two adjacent way stations, a line relay at each way station, two position means at each way station for either connecting the line relay at such way station to said one line circuit and connecting the adjacent sections of said another line circuit together or connecting the line relay at such way station to said another line and connecting the adjacent sections of said one line circuit together, and means for effecting successive operation of said two position means to cause the line relays of said way stations to be successively connected to said one line circuit and then successively connecting to said another line circuit and a railway signal at each way station controlled over said message wire through the medium of said line relays.

17. A train dispatching system for controlling the movement of trains in response to dispatcher controlled wayside signals comprising, a dispatcher's office; a plurality of way stations; a message wire and a common return wire connecting said dispatcher's office with each of said way stations, a dispatcher's bank of polar channel selecting relays with each relay having a plurality of polar contacts; a way station bank of polar relays divided into groups, one group for each way station,

one relay for each relay in the dispatcher's bank, and each relay having a plurality of polar contacts; means for simultaneously operating the polar relays of the dispatcher's bank and the corresponding polar relays of the way station bank to corresponding polar positions, a plurality of sequentially closed channel circuits, each including the said message wire and said common return wire and corresponding polar contacts of corresponding polar relays of said two relay banks; and means in the dispatcher's office for allowing closure of said channel circuits only for a time shorter than the time during which said polar contacts are closed.

15 18. A train dispatching system for controlling the movement of trains in response to dispatcher controlled wayside signals comprising, a dispatcher's office; a plurality of way stations; two stepping line wires, a message line wire and a common return line wire connecting said dispatcher's office with each of said way stations successively; a dispatcher's bank of polar channel selecting relays being operable through cycles of operation; a way station bank of polar channel selecting relays divided into groups, one group for each way station, and one relay for each relay in the dispatcher's bank, said way station bank being operable through cycles of operation; means for simultaneously operating the polar relays of the dispatcher's bank and the corresponding polar relays of the way station bank to corresponding positions, said means including one of said two stepping line wires during the first half of each cycle, and said means including the other of said two stepping line wires during the last half of each cycle; and a plurality of sequentially closed channel circuits, each including said message line wire, said common return line wire, and corresponding polar contacts of corresponding polar relays of the two relay banks.

19. In a traffic controlling system of the multiple impulse type for railroads, the combination with a central office, a plurality of field stations, a line wire connecting said office and the first field station which may be extended successively to more remote field stations, a line relay at each field station, a line relay at said central office, a series of stepping relays at each field station, a series of stepping relays at said office, 50 control circuits for said stepping relays controlled by actuation of the associated line relay in a manner to cause a field stepping relay to be actuated in synchronism with a corresponding stepping relay in said office, means governed by the last stepping relay of each field station relay series for extending said line wire to the next more distant station.

20. In a centralized traffic controlling system, a central office, a plurality of successively more remote field stations, a sectionalized line circuit the sections of which extend respectively from the central office to the first field station and from each station to a more remote station, a line relay in said line circuit at said central office, a line relay at each field station included in the section of line circuit extending from that station to the next less remote station, a series of stepping relays at said office and at each field station each series controlled by its associated line relay, and means including said stepping relays at said field stations for successively connecting the next section of said line circuit to

the next preceding section of line circuit extending to the central office.

21. A centralized traffic control system for transmitting controls and indications between a control office and a plurality of field stations comprising, a stepping line circuit organization including a line wire extending from the control office to the nearest station and from each station to the next more remote station, a series of stepping relays in the control office, a plurality of stepping relays at each field station, a line relay in the control office and a line relay at each field station respectively controlling the corresponding stepping relays, said line wire at the beginning of a cycle of stepping operation 10 extending to the first station nearest the control office only, and means controlled by the last stepping relay at each station for extending said line wire to the next more remote station to control the line relay at that next station, whereby 20 the stepping relays at each of the plurality of stations are operated only one station at a time beginning with the station nearest the control office in synchronism with corresponding relays of said series in the control office. 25

22. In a centralized traffic control system, in combination with a series of stepping relays in a control office and a plurality of stepping relays at each of a plurality of field stations, a stepping line circuit organization comprising line wire 30 sections respectively extending from the control office to the nearest station and from each station to the next more remote station, a line relay in said line circuit at the control office, a line relay at each station included in the line wire 35 section extending toward the control office, means for sequentially energizing the stepping relays at each station in response to the operation of its line relay, means for sequentially energizing the series of stepping relays in the control office in 40 response to the operation of the line relay in the control office, and means governed by the last stepping relay at each station for connecting said line wire sections to extend the line circuit to the next station more remote from the control office, whereby the stepping relays at each station in turn are operated sequentially in synchronism with certain corresponding stepping relays in the control office. 45

23. A normally-at-rest centralized traffic control system of the multiple impulse type for transmitting controls and indications between a control office and a plurality of field stations one at a time in succession comprising, a line circuit organization effective upon initiation of the system to provide a line circuit extending to the first station nearest the control office only, said line circuit organization including line wire sections extending from each station to the next more remote station, a polar line relay in each 50 station included in the polar line section extending toward the control office, a plurality of stepping relays at each station operated sequentially in response to a series of successive impulses applied to said line circuit when extended 55 to that station, and means at each station responsive to the last impulse of the series for that station for disconnecting the line relay at that station from said line circuit and extending said line circuit to the next more remote station. 60 70
